CLAIM

The ornamental design for a trouble light handle attachment, as shown and described.

DESCRIPTION

FIG. 1 is a top, front perspective view of a trouble light handle attachment showing my new design;

FIG. 2 is a side elevational view, the opposite side being a mirror image;

FIG. 3 is a bottom plan view thereof;

FIG. 4 is a rear elevational view thereof; and

FIG. 5 is a front elevational view thereof.
